SOUND ATTENUATING GAS PIPE

Edmund Ludlow, Columbus, Ind., assignor to Arvin Industries, Inc., Columbus, Ind., a corporation of Indiana

Filed Nov. 7, 1960, Ser. No. 67,756
16 Claims. (Cl. 181—48)

This invention relates to a sound attenuating pipe, and more particularly to a sound attenuating exhaust pipe for use in association with internal combustion engines for conveying the exhaust gases therefrom and for attenuating the noise level of said exhaust gases.

It is an object of my invention to provide a sound attenuating pipe which will convey the exhaust gases emanating from an internal combustion engine, which will attenuate the noise level of such exhaust gases, which will effect such sound attenuation over a wide range of frequencies, and which can be tuned to attenuate any desired range of frequencies. It is a further object of my invention to provide a pipe having such sound attenuating properties which can be easily and economically manufactured from metal-tubing, which will have limited space requirements, and which will provide an effective thermal insulation for hot exhaust gases.

In carrying out my invention in its preferred form, I provide an outer pipe having a plurality of inserts mounted therein, said inserts being coaxially aligned and defining a main gas-flow passage throughout their length in the outer pipe. Each of said inserts comprises an elongated tube section having an outwardly projecting bell at one of its ends and a slightly constricted neck at its opposite end. In assembly, the neck of one of said inserts is press-fit into the tube section of the next adjacent insert to thus form a substantially continuous main gas-flow passage. The bell on each of the inserts abuts the inner wall of the outer pipe, and with the ends of the adjacent pairs of inserts in interfitting engagement, each of said bells will thus support the adjacent ends of a pair of adjacent inserts in spaced relation to the inner wall of the outer pipe. Thus, each adjacent pair of inserts acts in combination with the adjacent wall of the outer pipe to define a resonating chamber volume.

The inserts are provided with elongated grooves formed in their restricted necks and, with each of said necks being received in the tube section of the next adjacent insert, said grooves and tube sections thus define elongated throat passages to dispose the resonating chamber volumes in operative communication with the main gas-flow passage whereby said volumes will effect an attenuation of the noise level of the exhaust gases.

Other objects and features of my invention will become apparent from the more detailed description which follows and from the accompanying drawings, in which:

FIG. 1 is an isometric view partially in section showing a sound attenuating exhaust pipe embodying my invention;

FIG. 2 is an enlarged fragmentary longitudinal section of the pipe shown in FIG. 1 taken in the plane of the line 2—2 of FIG. 3;

FIG. 3 is an enlarged vertical section taken on the line 3—3 of FIG. 2;

FIG. 4 is an enlarged isometric view of one of the inserts shown in FIG. 2;

FIG. 5 is an enlarged fragmentary longitudinal section of a modified form of my invention and taken in the plane of line 5—5 of FIG. 6 with the openings lying in the front of said plane being shown in dotted line;

FIG. 6 is a vertical section taken on the line 6—6 of FIG. 5; and

2

FIG. 7 is an enlarged isometric view of one of the inserts shown in FIG. 5.

In the operation of a conventional internal combustion engine in an automobile, the combustion of fuel within the cylinders produces a substantial volume of hot exhaust gases which are exhausted with substantial noise into one or more exhaust manifolds in communication with the exhaust ports of the several cylinders. The frequencies of the sound waves in such exhaust gases extend over a wide range, such as for example from about 30 cycles per second to about 5,000 cycles per second, and in many exhaust systems it is the lower range of frequencies, i.e., frequencies below 200 cycles per second, that are the most difficult to attenuate or silence. This low range of frequencies below 200 cycles per second is the most difficult to attenuate because the firing frequency of the engine falls within this range as does the natural resonance frequency of the exhaust system itself.

In a conventional automobile exhaust system, all of the silencing of the gases occurs in a muffler connected between an exhaust pipe joined to the exhaust manifold and a tail pipe leading from the muffler to a gas discharge point. Such mufflers conventionally comprise an outer shell having an elliptically or circularly shaped cross-section several times larger than the cross-section of the exhaust pipe, and having a relatively small number of tuned resonator chambers adapted to attenuate the noise level of the exhaust gases passing therethrough. In order for the muffler to achieve maximum silencing it is necessary that a pair of these chambers with large volumes be tuned to attenuate the narrow bands of the wave frequencies of the first overtones of the standing waves of the exhaust and tail pipes. All of these resonator chambers in the muffler are baffled from one another, and are arranged within the outer muffler shell in staggered patterns which, combined with the large volumes of the chambers for the exhaust and tail pipes, results in the muffler being rather large and difficult to mount within the limited space available on the underside of an automobile.

My invention is adapted to attenuate the noise level of the exhaust gases over a wide range of frequencies by passing said gases through a pipe construction containing a series of in-line inserts which provide a large number of small sound attenuating units disposed along the length of the exhaust system. These units are tuned to attenuate different, and overlapping, bands of wave frequencies so that the combinative effect of all of the inserts is an attenuation of the entire range of frequencies of the sound waves in the exhaust gases. While my invention may effect such an attenuation of the exhaust gas noises alone, if desired, it may also be used in combination with other in-line resonators, or a conventional muffler, or incorporated within a muffler as a muffler component, or in combination with an acoustical liner, such as is described in copending application Serial No. 67,527, filed November 7, 1960.

As shown in FIG. 1, my invention comprises an outer pipe 10 adapted to be connected at one of its ends to an exhaust manifold by a conventional mounting flange 12. Conveniently, the pipe 10 may have the same outer diameter of about 2.25 inches as is normally used in the exhaust pipes and tail pipes in conventional exhaust systems.

Mounted within the outer pipe 10 are a plurality of inserts 14 conveniently formed of lengths of metal-tubing. As shown, each of said inserts comprises an elongated tube section 16 having an annular outwardly projecting bell 18 at one of its ends. An elongated open-ended constricted neck 20 projects axially from the opposite end of the tube section 16. The outer diameter of the neck 20 approximates the inner diameter of the tube section

16 so that the neck 20 of one of said inserts may be press-fit into the tube section 16 of the next adjacent insert 14. In this manner, the interconnections between adjacent inserts are substantially gas-tight, and the several inserts thus form a continuous gas-flow passage throughout their axial length in the outer pipe. Alternatively, the diameter of the belled end of the tube section 16 may be stepped down, in which case the neck 20 will not have a restricted diameter, but due to the stepped down tube section diameter, the neck of one insert can still be 10 press-fit into the tube section of an adjacent insert (said alternative not being shown in the drawings).

In the assembly of my exhaust pipe, the series of inserts 14 are interconnected in the manner just described, and are then forced into the outer pipe 10 into a position such that said inserts will lie within the extent of the straight sections of said outer pipe. The tube sections 16 and necks 20 of the inserts are held in spaced relationship to the inner wall of the pipe 10 by the outwardly projecting annular bells 18 which abut the inner wall of 20 the pipe 10. As shown in FIG. 2, each of the bells 18 supports the end of the insert 14 upon which said bell is formed and the neck end of the next adjacent insert. With the inserts thus supported in spaced relationship to the pipe 10, each pair of adjacent bells 18 defines the end walls of a resonating chamber volume 22 having the configuration of an extended annulus, the side walls of said volumes being formed by the outwardly presented walls of the inserts 14 and the inwardly presented wall of the pipe 10. As will be apparent, the volumes 22 also serve as a thermal insulation for the exhaust gases passing through the inserts 14, and will further materially reduce the direct transmission of high frequency sound from the gas stream through the wall of the outer pipe.

The throats for the volumes 22 are formed by one or more grooves formed in the necks 20 and/or tube sections 16 of the inserts. In the illustrated embodiment of the insert, a pair of inwardly projecting, radially spaced grooves 23 and 24 of unequal length are formed in the neck 20, the groove 24 extending the length of said neck and the groove 23 extending only approximately one-half the length of said neck. Conveniently, an outwardly projecting, axially extending bead or groove 25 is also formed in the tube section 16 adjacent the bell 18. As will be understood, the neck portions forming the edges of the grooves 23 and 24 bear against the walls of the tube sections 16 of the next adjacent inserts to thus form axially extending volume throats interconnecting the main gas-flow passage with the resonator chamber volumes 22. Because the insert necks 20 are press-fit into the tube sections 16 of adjacent inserts, it is of course possible to adjust both the volume of the resonating volumes 22 and the length, cross-sectional area, and number of the volume throats formed by the grooves 23-25 so that the volumes 22 will attenuate a wide range of sound frequencies. For example, if the neck 20 of one of the inserts is forced a substantial distance into the tube section of the next adjacent insert with its grooves 23 and 24 out of radial alignment with the bead 25 of said tube section, a single elongated throat having a small cross-sectional area will be formed by the elongated groove 24 whereby the volume 22 in communication with said throat will attenuate a low range of frequencies. If the two adjacent inserts are maintained in this axial orientation, but are rotated with respect to each other to align the grooves 24 and 25, a single elongated throat having a larger cross-sectional area will be formed whereby the volume in communication therewith will attenuate a higher range of frequencies. However, if the two adjacent inserts are forced together a distance only sufficient to dispose the closed end of the groove 23 on one beyond the belled end of the other, both of the grooves 23 and 24 will form throats so that the volume in communication therewith will attenuate an even higher range of frequencies, and by rotating the inserts with respect to

5 each other to dispose one of the beads 23 or 24 in alignment with the bead 25 while they are in this axial orientation a still higher range of frequencies will be attenuated.

Thus, the several resonating chamber volumes and throats may be individually tuned to act upon a wide range of frequencies, including the difficult to silence range of frequencies below 200 cycles per second. In certain instances, for example when a series of the inserts 14 are slidably joined together to provide the desired tuning effect and then forced into the outer pipe 10, it may be desirable to weld or stake the inserts together to insure that the desired size and number of throats as well as the desired throat volume capacities are maintained when they are forced into position in the outer pipe.

As shown in FIG. 2, to support the neck end of the last insert in a series, a short insert is employed having only a bell 18 and a short tube section 16. In order to permit a full range of tuning for the resonating chamber volume in operative communication with this shortened terminal insert, it is, of course, necessary that its tube section have a length at least equal to the neck 20 of the insert over which it is press-fit and that it be provided with a groove 25.

Although I have described the grooves 23 and 24 as being formed in the insert necks and the grooves 25 in tube sections, it is, of course, possible to form the grooves 23 and 24 as outwardly projecting grooves in the tube sections 16 and the grooves 25 as inwardly projecting grooves in the necks. It is also possible to employ only single grooves in either the tube sections or the necks, in which instance it will be possible to form only one throat at the junction of each pair of inserts, the length of which can be adjusted to effect tuning.

25 A modified form of my invention is illustrated in FIGS. 5-7 and comprises an outer pipe 10' and a plurality of interconnected inserts 14' coaxially carried in said outer pipe and forming the main gas-flow passage. As shown, each of the inserts 14' is conveniently formed from a length of metal-tubing and comprises an elongated tube section 16' having an annular, outwardly projecting bell 18' at one of its ends. An elongated, open-ended, constricted neck 20' projects axially from the opposite end of said tube section. The outer diameter of the neck 20' approximates the inner diameter of the tube section 16' so that the neck 20' of one of said inserts may be press-fit into the tube section 16' of the next adjacent insert. In this manner, the interconnections between the adjacent inserts are substantially gas-tight and the several inserts thus form a continuous gas-flow passage throughout their axial length in the outer pipe 10'.

50 As shown in FIG. 5, the interconnected inserts 14' are maintained in a coaxial relationship within the outer pipe 10' by means of the bells 18', with each of said bells supporting the end of the insert upon which it is formed and the neck end of the next adjacent insert. As with the other modification of my invention, each pair of adjacent bells 18' defines the end walls of a resonating chamber volume 22' having the configuration of an extended annulus, the side walls of said volumes being formed by the outwardly presented walls of the inserts 14' and the inwardly presented wall of the pipe 10'. As shown in FIG. 5, the neck end of the last insert 14' in a series is supported by a short insert having only a bell 18' and short tube section 16'. Also shown in FIG. 5, the first insert 14' in a series will not have an insert received in its belled end, and its beads 26 and 27 will not have an adjacent underlying surface with which to form a resonator throat; with the result that, unless a sleeve having an aperture disposed in alignment with said beads is inserted in the belled end of the first insert, the resonator volume 22' formed by said first insert merely serves as an expansion chamber disposed in open communication with the gas stream by the bead openings 30.

75 A pair of outwardly projecting beads 26 and 27 having

different cross-sectional areas are formed on the tube section 16 adjacent the bell 18'. Each of the beads 26 and 27 extends around substantially the entire circumference of the tube section 16', but each has one of its ends closed as at 28 and its opposite end open as at 30. An opening 32 having a width at least equal to the axial distance between the remote sides of the pair of beads is formed in the neck 20' of each of the inserts in a position such that when a pair of the inserts 14' are disposed in interfitting engagement, the opening 32 on one of said inserts will be disposed in alignment with either the bead 26, or 27, or both, on the other of said pair of adjacent inserts. Thus, the beads 26 and 27 form arcuate volume throats for the resonating chamber volumes 22' disposed within the axial extent of their respective tube sections, the openings 30 and 32 constituting the terminal ends of said throats.

To tune a pair of the inserts shown in FIGS. 5 and 7, the neck 20' of one of said inserts is slid into the belled end of the tube section 16' of the adjacent insert so that its opening 32 is disposed in the desired alignment with the beads 26 and 27 on said adjacent insert. If the opening 32 is aligned with just one of said beads a single throat will be formed, and the two inserts may then be rotated with respect to each other to adjust the arcuate spacing between the openings 32 and 30 to thus provide the desired length for said throat for effecting the desired tuning. Of course, when a pair of inserts are rotated to dispose the opening 32 of one immediately adjacent the closed end 28 of one of the beads 26 or 27 on the other, the longest possible single throat will be formed, and the volume 22' in communication therewith will attenuate extremely low bands of frequencies. By placing the opening 32 in alignment with both beads, a pair of throats are formed which may be tuned by rotating the inserts with respect to each other to adjust the arcuate spacing between the opening 32 and the open ends 30 of the two beads. As with the other modification of my invention, where two throats are formed the volume 22' in communication therewith will attenuate a higher range of frequencies than where a single throat is employed. When the inserts are in the desired axial and rotational position with respect to each other, they may be rigidly secured together as by welding and then placed in the outer pipe 10' to produce resonators attenuating at the desired range of frequencies.

Of course it is possible for either of the beads 26 or 27 to be open at both of its ends, that is at 28 and 30, in which instance that bead will form with the neck opening 32 a pair of throats acting in parallel. However, in such a situation the pair of throats act in combination with each other and the volume in communication therewith to produce, in effect, a single throat for said volume, said single throat having an effective length shorter than the actual length of either of the two actual throats to thus cause the volume to attenuate a higher band of wave frequencies than if the volume were in communication with only the shorter of the two throats.

It is of course possible to have an alternative construction of the insert 14' in which the beads 26 and 27 project inwardly from the neck 20' and the opening 32 is formed in the tube section 16'. And it is possible to step down the diameter of the belled end of the tube section 16' in which case the neck 20' will not have a restricted diameter, but due to the stepped down tube section diameter, the neck of one insert can still be press-fit into the tube section of an adjacent insert.

As will be understood, when my invention is not used as the sole means for silencing the exhaust gases of an automobile engine, such as for example when it is used in combination with a conventional muffler or as a component of such a muffler, the inserts are merely joined together to provide the desired tuning of the resonating chamber volumes and throats and are placed in a short length of an outer pipe. These shorter outer pipes con-

taining the resonators may then be employed as sections of the exhaust pipes interconnecting the manifolds and mufflers, or used as components of conventional mufflers, in which case they are merely mounted within the outer muffler shells.

While my invention has been described for use in an exhaust system, it may, of course, be used on the intake side of an internal combustion engine for transporting and silencing the gaseous mixtures into the engine, or in any other applications involving the movement and silencing of gases.

I claim as my invention:

1. In a sound attenuating gas pipe for conveying and attenuating the noise level of a moving gas stream, an outer pipe, a plurality of aligned inserts mounted within said outer pipe, each of said inserts comprising a tube section having an axially projecting neck at one of its ends and an outwardly projecting bell at its opposite end, the neck on each of said inserts being inserted into the tube section of the next adjacent insert and supported against the inner walls of said tube section of said next adjacent insert to interconnect said inserts and form a main gas-flow passage, the bells on said inserts engaging the inner wall of the outer pipe to support the tube sections and necks of the inserts in spaced relation to the outer pipe and define the end walls of a plurality of resonator volumes interposed between the inserts and outer pipe, and means on the interconnected ends of each pair of inserts forming at least one elongated open-ended throat joining one of said volumes to said main gas-flow passage for attenuating the noise level of the gas stream moving through said passage.

2. The invention as set forth in claim 1 in which the distance between the outer faces of the opposed walls of the necks approximates the distance between the inner faces of the opposed walls of the tube sections whereby said necks are press-fit into said tube sections to form substantially gas-tight joints between adjacent inserts.

3. The invention as set forth in claim 1 in which said means are axially oriented on said inserts, and a plurality of said inserts are inserted different lengths into their next adjacent inserts to provide pluralities of volumes of different sizes and throats of different lengths.

4. The invention as set forth in claim 1 in which said means are arcuately oriented on said inserts, and a plurality of said inserts are disposed in different angular orientations with respect to their next adjacent inserts to provide a plurality of throats of different lengths.

5. The invention as set forth in claim 1 in which said means are axially and arcuately oriented on said inserts, and a plurality of said inserts are inserted different lengths at different angular orientations into their next adjacent inserts to provide pluralities of volumes of different sizes and throats of different lengths.

6. The invention as set forth in claim 1 in which said means on the interconnected ends of each pair of inserts comprises at least one axially extending groove formed in the end of one of said pair of inserts and the portion of the side wall of the other of said pair of inserts in alignment with said groove.

7. The invention as set forth in claim 1 in which said means on the interconnected ends of each pair of inserts comprises a plurality of axially extending grooves of different axial lengths formed in the end of one of said pair of inserts and the portion of the walls of the other of said pair of inserts in alignment with said grooves, said pair of inserts being axially adjustable with respect to each other for adjusting the length and number of said throats joining said one volume to the main gas-flow passage.

8. The invention as set forth in claim 1 in which said means on the interconnected ends of each pair of inserts comprises at least one axially extending groove formed in the neck end of one of said pair of inserts and at least one axially extending groove formed in the belled end of

the tube section of the other of said pair of inserts, said pair of inserts being axially and rotatably adjustable with respect to each other for adjusting the length and cross-sectional area of the throat formed by said grooves.

9. The invention as set forth in claim 1 in which said means on the interconnected ends of each pair of inserts comprises at least one arcuately extending bead formed on one of said pair of inserts adjacent an end thereof and the portion of the side wall of the other of said pair of inserts in alignment with said bead, said bead having at least one opening disposed within the extent of one of said volumes and said side wall having an opening formed therein within the extent of said bead.

10. The invention as set forth in claim 9 in which said bead extends substantially circumferentially around said one of said pair of inserts and has one of its ends closed and its opposite end open.

11. The invention as set forth in claim 9 in which said pair of inserts are rotatably adjustable with respect to each other for adjusting the arcuate distance between said side wall and bead openings for adjusting the length of the throat formed by said pair of inserts.

12. The invention as set forth in claim 9 in which said side wall opening has a width at least as large as the width of the beaded area of said one of said pair of inserts.

13. The invention as set forth in claim 1 in which said means comprises a plurality of outwardly projecting, arcuate beads formed on the tube section of one of said pair of inserts and the portion of the outer wall of the neck of the other of said pair of inserts in alignment therewith, each of said beads having an opening formed therein in communication with one of said volumes and said neck portion in alignment with the beads having an opening formed therein in communication with the main 35 gas-flow passage.

14. The invention as set forth in claim 13 in which said plurality of beads are axially spaced along said tube

section, and the opening in said neck has an axial length at least as long as the distance between the remote side walls of the remote beads of said plurality of beads, said pair of inserts being movable with respect to each other for selectively positioning said neck opening in axial alignment with said beads and for adjusting the arcuate spacing between said bead and neck openings.

15. In a sound attenuating gas pipe for conveying and attenuating the noise level of a moving gas stream, an outer pipe, a plurality of interfitting, axially extending, open-ended inserts carried in the outer pipe and defining a main gas-flow passage, the axially extending walls of said inserts being spaced from said outer pipe and acting in combination with said outer pipe and means supporting said axially extending walls in spaced relation to said outer pipe to form a plurality of closed axially extending resonating chamber volumes interposed between the main gas-flow passage and the outer pipe, and means on said inserts forming at the juncture of each pair of inserts at least one elongated open-ended volume throat to dispose each of said volumes in operative communication with said main gas-flow passage.

16. The invention as set forth in claim 12 in which said inserts are adjustably movable with respect to each other for adjusting the lengths of said throats.
